ATTYS.

UNITED STATES PATENT OFFICE.

DANIEL J. GOLDEN, OF BROCKTON, MASSACHUSETTS.

SPORTING-SHOE.

1,278,140.

Specification of Letters Patent. Patented Sept. 10, 1918.

Application filed May 9, 1918. Serial No. 233,562.

To all whom it may concern:

Be it known that I, DANIEL J. GOLDEN, a citizen of the United States, residing at Brockton, in the county of Plymouth and 5 State of Massachusetts, have invented new and useful Improvements in Sporting-Shoes, of which the following is a specification.

This invention relates to shoes to be worn 10 by players of basket ball, tennis, etc., the outer sole of the shoe being of elastic material, such as rubber, adapted to have a clinging contact with the floor, or other surface on which the wearer stands, the 15 upper of the shoe including an exposed portion of leather, or other material, having suitable wear-sustaining characteristics, and presenting a neat and desirable appearance.

20 The object of the invention is to provide an improved construction whereby the area of the leather portion of the upper is reduced to minimize the cost of the material, and a secure and durable connection is provided between the exposed portion of the 25 upper and the rubber outer sole.

The invention is embodied in the improvements which I will now proceed to describe and claim.

30 Of the accompanying drawings, forming a part of this specification,—

Figure 1 is a side elevation of a partly completed shoe embodying the invention.

Fig. 2 is a section on line 2—2 of Fig. 1.

35 Fig. 3 is a side elevation of the completed shoe, a portion of the upper being broken away.

Fig. 4 is a section on line 4—4 of Fig. 3.

40 Figs. 5 and 6 are sectional views illustrating different modes of operation of connecting the rubber outer sole with the upper.

Fig. 7 is an enlarged fragmentary sectional view illustrating a reinforced construction.

45 The same reference characters indicate the same parts in all of the figures.

In making the upper of my improved shoe, I assemble a top member 12 which includes portions of the vamp and quarters, 50 and is docked at its lower portion so that its lower edge is spaced from the inner sole of the shoe, and a textile fabric member 13, which includes supplemental portions of the vamp and quarters and is secured to the 55 lower edge portion of the top member, preferably by a line of stitches 14. The top member 12 is preferably of leather, and the

fabric member 13 is preferably composed of duck or canvas having suitable tensile strength. I prefer to form the fabric member 13 as a lining which is co-extensive with the top member 12, and is attached thereto in the usual or any suitable manner, the lower portion of the member 13 projecting below the top member and being attached to 60 the inner sole 15. As here shown, the lower edge of the member 13 is turned inwardly upon the inner sole and is secured thereto by clenched fastenings 16, such as lasting tacks driven during the operation of lasting the 65 upper upon the inner sole.

It will be seen by reference to Figs. 1 and 2, that when the upper is lasted, the lower edge of the top member 12 forms a downwardly facing shoulder which is spaced 70 above the inner sole.

17 represents an elastic outer sole made of rubber, or a composition containing rubber, said outer sole being formed to extend from end to end of the shoe and being preferably thickened at its rear portion to form a heel, and at its fore portion to form a tread, the intermediate portion being preferably reduced in thickness to form a shank.

18 represents an upstanding flange which, 85 in the completed shoe coheres to and covers the margin of the outer sole, and also coheres to and covers the portion of the fabric member 13 between the inner sole and the top member 12, or below the lower edge of 90 said top member. The flange 18 is of textile fabric, which may be frictioned and caused to cohere both to the outer sole and to the fabric member 13 by the process of vulcanization, the vulcanization of the outer 95 sole being completed after the flange 18 is applied thereto, and the projecting portion of the flange 18 being vulcanized to the fabric member 13. The flange 18 may be applied to the member 13 before its attachment to the outer sole, as indicated by

Fig. 5, or after its attachment to the outer sole, as indicated by Fig. 6. It will be understood that the flange 18 may be caused to cohere to the outer sole and to the fabric 100 member 13 in any suitable way, or by any suitable process which will result in a firm union between the said parts. The cohesion may be caused, therefore, by a vulcanizing process, or by a process such as the so-called 105 "acid" process practised without heat.

The flange 18 is preferably so formed at its upper edge that it abuts against the shoulder formed by the lower edge of the

top member 12, as shown by Figs. 3 and 4, the outer surface of the flange 18 and the outer surface of the top member 12 being substantially flush with each other. It will 5 be seen that the flange 18 may be made of a single layer of textile fabric, such as duck or canvas, or of a plurality of layers suitably and intimately connected. The fabric member 13 may also consist of a single layer, 10 or a plurality of intimately connected layers.

As shown by Fig. 7, the fabric member 13 does not necessarily cover the entire inner surface of the top member 12, and it may be formed as a relatively narrow strip 15 secured near its upper edge to the top member 12 by the stitches 14. Fig. 7 shows the fabric member 13 provided with a reinforcing member 13^a, which may be a layer of any suitable reinforcing material which 20 may be attached to the textile fabric member, the top member, and the inner sole.

It will now be seen that the docking of the top member 12 results in a considerable saving of the material of the top member, 25 which is an important consideration when said member is made of leather. It will also be seen that the fabric member 13 firmly secured to the top member, as by the stitches 14, and by the usual stitches at other 30 parts of the upper, and secured to the inner sole by means such as the lasting tacks 16, constitutes a strong and durable connection between the top member and the inner sole, the textile fabric flange, united as described, 35 to the fabric member 13, and to the rubber outer sole, constituting a secure connection between the upper and the outer sole.

I claim:

1. A shoe comprising an inner sole, an 40 upper composed of a docked top member which includes portions of the vamp and quarters, and has its lower edge spaced from the inner sole, and a textile fabric member which includes supplemental portions of the 45 vamp and quarters, and is secured to the top member, and to the inner sole, a rubber outer sole, and an upstanding flange of textile fabric secured to the margin of the outer sole and to said fabric member.
2. A shoe comprising an inner sole, an 50 upper composed of a docked top member which includes portions of the vamp and quarters, and has its lower edge spaced from the inner sole, and a textile fabric 55 member which includes supplemental portions of the vamp and quarters, and is secured to the top member, and to the inner sole, a rubber outer sole, and an upstanding flange of textile fabric secured to the margin of the outer sole and to said fabric member, the upper also including an internal reinforcing member attached to the textile fabric member, the top member, and the inner sole.
3. A shoe comprising an inner sole, an 60 upper composed of a docked top member which includes portions of the vamp and quarters, and has its lower edge spaced from the inner sole, and a textile fabric member formed as a lining for the top member and projecting below the latter to constitute supplemental portions of the vamp and quarters, said fabric member being secured to the lower edge portion of the top member and to the inner sole, a rubber outer sole, and an upstanding flange of textile fabric 65 secured to the margin of the outer sole and to said fabric member.
4. A shoe comprising an inner sole, an upper composed of a docked top member which includes portions of the vamp and quarters 70 and has its lower edge spaced from the inner sole, and a textile fabric member which includes supplemental portions of the vamp and quarters, stitches securing said fabric member to the lower edge portion of the top member, fastening means securing the fabric member to the inner sole, a rubber outer sole, and an upstanding flange of textile fabric 75 cohering to and covering the margin of the outer sole and the said fabric member between the inner sole and the lower edge of the top member.
5. A shoe comprising an inner sole, an upper composed of a docked top member which includes portions of the vamp and quarters and has its lower edge spaced from the inner sole, and a textile fabric member 80 formed as a lining for the top member and projecting below the latter to constitute supplemental portions of the vamp and quarters, stitches securing said fabric member to the lower edge portion of the top member, fastening means securing the fabric member to the inner sole, a rubber outer sole, and an upstanding flange of textile fabric 85 cohering to and covering the margin of the outer sole and the said fabric member between the inner sole and the lower edge of the top member.
6. A shoe comprising an inner sole, an upper composed of a docked top member which includes portions of the vamp and quarters, and has its lower edge spaced from the inner sole, and a textile fabric member which includes supplemental portions of the vamp and quarters, and is secured to the top member, and to the inner sole, a rubber outer sole, and an upstanding flange of textile fabric 90 secured to the margin of the outer sole and the said fabric member between the inner sole and the lower edge of the top member.

In testimony whereof I have affixed my signature.

DANIEL J. GOLDEN.
